CREAMER OR SIMILAR ARTICLE

Frank J. Benes, Lancaster, Ohio, assignor to Anchor Hocking Glass Corporation, Lancaster, Ohio, a corporation of Delaware

Original design application Apr. 20, 1967, Ser. No. 6,764. Divided and this application Dec. 5, 1967, Ser. No. 9,903

Term of patent 14 years

(Cl. D44—21)

FIG. 1 is a side elevational view of a creamer or similar article showing my new design;

FIG. 2 is a rear view thereof; and

FIG. 3 is a top view thereof.

The present application is a division of co-pending United States design patent application Ser. No. 6,764 filed Apr. 20, 1967.

I claim:

The ornamental design for a creamer or similar article, substantially as shown and described.
